UNITED STATES PATENT OFFICE.

CALVIN ADDISON EVA, OF AUSTIN, TEXAS.

BELT ATTACHMENT.

Application filed January 16, 1923. Serial No. 612,954.

To all whom it may concern:

Be it known that I, CALVIN ADDISON EVA, a citizen of the United States, and a resident of Austin, in the county of Travis and State 5 of Texas, have invented certain new and useful Improvements in Belt Attachments, of which the following is a specification.

This invention relates to pencil clips especially adapted for application to one's belt 10 or other part of one's garment.

Briefly stated an important object of this invention is to provide a simple and reliable means whereby the pencil may be carried on one's belt in such a manner that the pencil 15 is highly accessible and may be detached from the clip without effort on the part of the operator.

Another object is to provide a clip of the character specified which is extremely neat 20 and inconspicuous, durable in use and cheap to manufacture.

Other objects and advantages of the invention will appear during the course of the following description.

25 In the accompanying drawing, forming a part of this application and in which like numerals are employed to designate like parts throughout the same,

Figure 1 is a perspective of the improved 30 clip applied, the belt being shown in use.

Figure 2 is an enlarged perspective of the improved clip applied to a belt and detachably supporting a pencil.

Figure 3 is a perspective of the clip 35 detached.

Figure 4 is a vertical transverse sectional view through the clip applied.

In the drawing wherein for the purpose 40 of illustration is shown a preferred embodiment of the invention, the numeral 5 designates the improved clip which may be formed from a suitable metal and which is bent intermediate its ends to define a loop 6 for the reception of a belt 7, the ends 86 of 45 the loop are extended diagonally and have

connection with the top or outer walls 8 of the loop. With reference to Figure 3 it will be observed that the outer walls 8 are formed with outwardly directed portions or leaves 12 which flatly contact with the opposite 50 sides of a pencil 16 so as to detachably hold the pencil in position. It will be observed that the edge portions of the upper and lower leaves 12 are curved inwardly as indicated at 18 so as to hold the pencil in 55 position. It might be stated that the edge portions 18 are curved inwardly to approximately conform to the curvature of the pencil and to prevent the pencil from being removed by a lateral movement. 60

In summarizing it will be seen that the invention consists of a metallic open sided loop, one side of which is formed with outwardly directed leaves preferably of spring 65 metal which engage the opposite sides of the pencil so as to hold the pencil in position.

In use the clip provides an extremely simple and reliable means whereby a pencil may be carried on one's person and it will 70 be seen that the improved clip may be manufactured at an extremely low cost.

Having thus described the invention, what is claimed is:—

As an article of manufacture, a belt attachment formed from a single length of spring metal having its intermediate portion formed with an open-sided loop adopted to receive a waist encircling belt, the upper and lower walls of said loop being inclined 75 to engage the edges of said belt, the terminal portions of said length of metal being extended outwardly in approximately parallel relation to define gripping members adapted to flatly contact with opposite sides of a 80 writing pencil, and the terminal portions of said gripping members being extended inwardly to securely hold the pencil in position. 85

CALVIN ADDISON EVA.
